(57) **CLAIM**

The ornamental design for a fashion jewelry clip as shown and described.

DESCRIPTION

FIG. 1 is a front elevation view of a fashion jewelry clip, showing my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a front perspective view thereof;

FIG. 8 is a rear perspective view thereof; and,

FIG. 9 is another front perspective view thereof with an environmental structure shown in broken lines.

The broken lines in the drawings illustrate portions of the fashion jewelry clip that form no part of the claimed design. The broken line showing of a portion of a hat is for the purpose of illustrating environmental structure and forms no part of the claimed design.
